UNITED STATES PATENT OFFICE.

JOSEPH S. BLACKBURN, OF SALEM, OHIO.

WIRE-FEEDING DEVICE.

SPECIFICATION forming part of Letters Patent No. 463,935, dated November 24, 1891.

Application filed March 19, 1891. Serial No. 385,698. (No model.)

To all whom it may concern:

Be it known that I, JOSEPH S. BLACKBURN, of Salem, in the county of Columbiana and State of Ohio, have invented a new and Improved 5 Wire-Feed, of which the following is a full, clear, and exact description.

The object of the invention is to provide a new and improved wire-feed more especially designed for use on nailing-machines, and 10 which is simple and durable in construction and very effective and positive in operation.

The construction and arrangement of parts constituting the device are as hereinafter described, with reference to accompanying drawings, in which—

Figure 1 is a face view of the improvement in an open position. Fig. 2 is a plan view of the same, and Fig. 3 is a face view of the improvement in a closed or gripping position.

The improvement is mounted on a plate A, provided with two pivots B and B', on which are mounted to swing the parallel levers C and D, respectively, connected by pivots E and E', respectively, with a jaw F, mounted 25 to slide on the plate A, and opposite which is arranged a second jaw G, between which two jaws F and G the wire is gripped and fed to the desired place. The jaw G carries pivots H and H', connecting said jaw with the outer 30 curved ends of the levers C and D, respectively, so that the two jaws F and G are arranged parallel and are pivotally connected with the two parallel levers C and D. On the front of the jaws F and G are arranged the 35 pivots I and I', respectively, connected with each other by a plate J, serving to hold the wire in place between the two jaws and the back plate A and the said plate J. A spring K, held on the plate A, presses with its free

end on the lever D, so as to hold the two jaws 40 F and G in a closed position—that is, gripping the wire. The opening movement of the parallel levers D C and the jaws F G is limited by a stop-pin L, secured on the plate A.

The operation is as follows: The wire is 45 passed between the two adjacent faces of the jaws F and G. The spring K, pressing on the lever D, forces the said jaws F and G shut, so as to firmly grip the wire. (See Fig. 3.) When the levers C D and jaws F G swing in the 50 direction of the arrow a' then the two jaws F and G move from each other, so as to disengage the wire.

Having thus described my invention, I claim as new and desire to secure by Letters 55 Patent—

1. In a wire-feed, the combination, with the plate A, of the two horizontal parallel movable jaws F G, the two vertical parallel levers C D, pivoted to said plate at one end and to 60 said jaws at the other, a spring acting against the levers, and the plate J, pivoted to and connecting the jaws, as shown and described, whereby the parts are adapted to operate as specified.

2. In a wire-feed, the combination, with the plate A and the two parallel horizontal jaws F G, of the two levers C and D, which are pivoted to the plate and jaws at their respective ends and arranged between them, as 70 shown, and the plate J, pivoted to the outer sides of the jaws and thereby connecting them and serving to hold the wire between the jaws, as shown and described.

JOSEPH S. BLACKBURN.
